SWITCH DEVICE FOR FIRE-ALARMS.

1,169,194.

Specification of Letters Patent.

Patented Jan. 25, 1916.

Application filed August 3, 1914. Serial No. 854,735.

To all whom it may concern:

Be it known that we, GEORGE B. RATTERMANN and WALTER W. GARRISON, citizens of the United States, residing at Birmingham, in the county of Jefferson and State of Alabama, have invented a new and useful 5 Switch Device for Fire-Alarms, of which the following is a specification.

This invention has reference to switch devices for fire alarms, and its object is to provide a normally inactive switch movable automatically to the closed position on the attainment of a predetermined degree of heat at the device.

15 The invention comprises a block of a suitable material, preferably, although not necessarily, refractory material, in which are mounted terminals for the attachment of electric conductors, one of the terminals being provided with a portion having a normal tendency toward the other terminal to thereby close the electric circuit when the device is properly installed. The parts however are so arranged that the circuit is 20 maintained open by fusible or other similar material, the continuity of which is destroyed by the attainment of a certain temperature or the presence of a flame at the device permitting the circuit closing member to move under its normal tendency into 25 circuit closing position. For the protection of the parts there is provided a casing arranged to in most part close in the block and the parts carried thereby, but with the 30 fusible member, which may be taken as typical of either a member which will melt at a predetermined heat or one which will burn or be otherwise destroyed, exposed.

35 The invention will be best understood 40 from a consideration of the following detailed description, taken in connection with the accompanying drawings forming a part of this specification, with the further understanding that while the drawings show a 45 practical form of the invention, the latter is not confined to any strict conformity with the showing of the drawings, but may be changed and modified so long as such 50 changes and modifications mark no material departure from the salient features of the invention.

55 In the drawings:—Figure 1 is a perspective view of a heat responsive device or fuse box of the present invention. Fig. 2 is a longitudinal vertical central section of the

structure shown in Fig. 1. Fig. 3 is a section on the line 3—3 of Fig. 2. Fig. 4 is a section on the line 4—4 of Fig. 2 but with the electric conductors omitted. Fig. 5 is a perspective view of the carrier block and parts fast thereto with the casing omitted. Fig. 6 is a perspective view of the base member of the casing. Fig. 7 is a perspective view of one end of the casing. Fig. 8 is a perspective view of the other end member of the casing. Fig. 9 is a perspective view of a form of fusible strip adapted to the present invention.

Referring to the drawings, there is shown a block 1 which may be of general rectangular form with parallel side wings 2 projecting from one face of the block, which face may be considered the inner or rear face. Through the body portion of the block between the wings there is formed a curved slot 3 near one end of the block. While the block may be made of various materials, it may be very conveniently constructed of porcelain without, however, limiting the invention to such particular material. Secured to the inner face of the block between the wings 2, but near one of them, is a conducting strip 4, and near the other wing there is a conducting plate 5. The strip 4 is provided with an angle extension 6, which enters the slot 3, but need not pass therethrough, and in the showing of the drawings does not pass therethrough. The plate 5 has one edge upturned, as shown at 7, and this upturned edge is continued toward the slot 3 in the form of a spring arm or finger 8 having an angle extension 9 at its free end long enough to pass through the slot 3 and beyond the outer face of the block 1 for a distance, and at its outer extremity is curved away from the side of the block near which the plate 5 is located, this curved away portion being indicated at 10 and is provided with an entering slot 11. Fast to the outer face of the block 1 adjacent to that end of the slot 3 near the wing 2 adjacent to which the plate 5 is secured, there is a bracket 12 having an outstanding leg 13 with the free end 14 curved, and also provided with an entering slot 15 similar to the end 10 of the extension 9 of the arm 8. There is also provided a strip 16 having enlarged ends 17, said strip being customarily made of some fusible material of considerable tensile strength, but which will yield 100 105 110

at a relatively low heat, there being certain well known alloys having these characteristics, and some metals also have these characteristics to an extent sufficient for the purposes of the present invention. Under some circumstances materials readily destructive by the direct action of flame or intense heat may be used in place of the fusible strip 16.

The recesses 11 and 15 are shaped to receive the strip 16 with the heads or enlargements 17 seated in the concave sides of the curved ends 10 and 14, while the length of the strip 16 is sufficient to hold the end 9 of the arm 8 a suitable distance from the contact 6, the extension 9 of the arm 8 also serving as a contact. The arm 8 is so shaped and located that in its free condition it engages forcibly with the contact 6, but when constrained by the strip 16 the length of the latter is such that the arm 8 is a material distance from the contact 6. The position of the arm 8 under the constraint of the strip 16 is shown in full lines in Fig. 3, and its position when freed from the constraint of the strip 16 is shown in dotted lines in Fig. 3.

In order to support and shield the block 1 and the parts carried thereby, there is provided a flat plate 18 constituting a base plate, and this is provided with perforations 19 for the passage of screws or other fastening devices, whereby the base plate 18 may be secured to a side wall or ceiling, or to any structure to which it is desired to attach the device of the present invention. The opposite edges of the plate 18 are formed with inturned flanges 20 providing channels for the reception of other members.

There is also provided a casing member 21 of sufficient width to receive the base 1 and having sides 22 with outstanding marginal flanges 23 at the edges remote from the face portion of the casing, and these sides 22 are of sufficient depth to provide for the inclosure of the block 1 when the flanges 23 are engaged in the channels of the inturned flanges 20. The casing member 21 has an end portion 22a corresponding to the sides 22 and this end portion is formed with spaced entering recesses 23a at the edge remote from the face portion of the casing member 21. There is also provided another casing member 24 having sides 25 with edge flanges 26 and an end 27 with entering recesses 28 all similar to like parts of the casing member 21. The casing member 24 has in its outer or face portion a recess 29 corresponding in shape to the slot 3.

When the parts are assembled the base plate 18 is made fast to the ceiling, wall or partition or other support, and the block 1 is placed upon the plate 18 with conductors 30 made fast by screws 31 to the strip 4 and plate 5 and where the fuse device forms a part of a system other conductors 32 are made fast to the strip 4 and plate 5 by screws

33. Now the casing member 21 is applied to the plate 18 with the flanges 23 seated in the flanges 20, and is moved along until the end 22a is against the corresponding end of the block 21, the recesses 23a providing for the passage of the conductors 30. The casing member 24 is applied to the plate 18 in a similar manner, but from the opposite end, and closes in the corresponding end of the block 1, but the recess 29 provides for the exposure of the slot 3 and movement of the end 9 of the arm 8. By this means the block 1 with parts carried thereby is quite efficiently covered and protected from harm, while the readily fusible strip 16 is exposed, so as to be quickly affected by undue heat or under some conditions by the action of flame, although it is the intention that the fusible member shall have its continuity destroyed long before flame would usually reach it. 85

In an installed fire alarm system the fuse boxes of the present invention are distributed as may be deemed necessary and the circuit closing arms 8 are arranged in multiple in the circuit where two or more boxes are included in one circuit. In the event of a fire or the presence of undue temperature, the strip 16 melts or so softens that the pull of the spring arm 8 will rupture and then the extension 9 comes into engagement with the contact 6, thus completing the circuit between the conductors 30 or the conductors 32, as the case may be, and by the inclusion of a suitable source of current, and an audible or visible alarm structure in the circuit, the alarm is given and will continue so long as the circuit remains intact. 95 100

By the provision of a divided casing made up of the parts 21 and 24, the block 1 may be effectively inclosed with the slot 3 and the passages 23 and 28 open, while usually the passages 23 and 28 will be quite well filled by the electric conductors, or may be otherwise filled. Dust and the like has little opportunity to find access to the structure for the only point of access is the slot 3, and this may be quite small, since it is only necessary to provide for a short movement of the arm 8. 110

What is claimed is:—

1. A fire alarm fuse box comprising a 115 casing, a block housed therein and having a slotted wall adjacent to the front of the casing and the latter having an opening therethrough matching the slot in the wall of the block, electric contacts carried by the inner face of the portion of the block adjacent to the front of the casing and provided with extensions, one of which projects through both the slot in the block and the front of the casing, a bracket fast to the block and extending through the slot in the front of the casing, and a fuse strip carried by the bracket and extended contact, the said extended contact having a normal tendency toward the other contact 120 125 130

and held from engagement therewith by the fuse strip.

2. A fire alarm fuse box comprising a block having a slot at one end and side 5 wings for spacing the block from a supporting member, electric contacts carried by the inner face of the block between the wings with one contact having a normal tendency toward the other, and provided 10 with an extension projecting through the slot and there having a curved extremity with an entering slot thereat, a bracket fast to the outer face of the block and having an outstanding part with a curved extremity 15 having an entering slot, and a fuse strip provided with enlarged heads at the ends adapted to engage behind the curved extremities of the contact and bracket with the fuse strip spacing the contacts apart.
- 20 3. A fire alarm fuse structure comprising a block having a slot therethrough and provided with side wings constituting spacing members, electric contacts carried by the inner face of the block between the wings, 25 and one contact having a normal tendency toward the other and provided with an extension projecting through the slot, a bracket carried by the block and matching the extension of the extended contact, a 30 fuse strip adapted to engage the connections and hold the extended contact out of

engagement with the other contact, and a casing inclosing the block and through which the bracket and extended contact project to carry the fuse strip exterior to the 35 casing.

4. A fire alarm fuse structure comprising a U-shaped block with a slot through the intermediate wall, an electric contact carried by the block between the sides thereof 40 near one end of the slot, another contact having a normal tendency toward the first contact and provided with an extension projecting through the slot, a bracket carried by the block near the other end of the slot 45 and exterior thereto, said bracket and extended contact having seats at the outer extremities, a fuse strip with heads at the ends adapted to the seats and of a length to hold the extended contact out of engagement with the other contact, and a casing 50 housing and carrying the block with the fuse strip exterior to the front wall of the casing.

In testimony, that we claim the foregoing 55 as our own, we have hereto affixed our signatures in the presence of two witnesses.
